ELECTRIC LAMP BASE

David Borowitz, Chicago, Ill.

Application January 19, 1955, Serial No. 34,060

Term of patent 3½ years

(Cl. D48—20)

Fig. 1 is a front elevational view of an electric lamp base showing my new design;

Fig. 2 is a right hand side view thereof; and

Fig. 3 is a top plan view thereof.

The left hand side view would be the same as the right hand side view.

The dotted lines indicating the lamp socket of Figs. 1 and 2 have been omitted from Fig. 3 for convenience of illustration.

The dominant features of my new design lie in the portions shown in full lines.

I claim:

The ornamental design for an electric lamp base, substantially as shown and described.
